UNITED STATES PATENT OFFICE.

WILLIAM ASBURY, OF NEW YORK, N. Y., ASSIGNOR TO STRAIGHT LINE REGULATOR CORPORATION, OF NEW YORK, N. Y.

CLOSURE OPERATOR.

1,407,828.

Specification of Letters Patent. Patented Feb. 28, 1922.

Application filed July 12, 1918. Serial No. 244,468.

To all whom it may concern:

Be it known that I, WILLIAM ASBURY, citizen of the United States, and resident of New York, in the county of New York and 5 State of New York, have invented certain new and useful Improvements in Closure Operators, of which the following is a specification.

This invention relates to closure operators, 10 and its particular object is to provide means for conveniently and easily raising and lowering a window sash. While the invention is primarily intended for use in connection with the windows of automobiles and the 15 like, nevertheless it will be understood that the principles involved herein may be utilized in other connections if desired.

A further object is to provide an operating mechanism by which a window sash may 20 be readily lifted and otherwise moved to the end that the weight of the sash may be transported off of the lifting mechanism.

A further object is to provide a device of 25 this character in which all of the parts are suitably supported and tensioned so that no rattling of the parts is possible at any time.

A further object is to provide means co-operative directly between the sash and the 30 operating element adapted to stand under tension at all times in a manner so as to prevent rattling of the parts.

A further object is to provide the device 35 with means whereby it will serve positively to support the window sash in any position of adjustment to which the sash may be elevated.

Other objects and aims of the invention, 40 more or less specific than those referred to above, will be in part obvious and in part pointed out in the course of the following 45 description of the elements, combinations, arrangements of parts and applications of principles, constituting the invention; and the scope of protection contemplated will be indicated in the appended claims.

In the accompanying drawings which are 50 to be taken as part of this specification, and in which I have shown merely a preferred form of embodiment of the invention:

Figure 1 is a side elevational view of a 55 closure operating device constructed in accordance with this invention.

Fig. 2 is a plan view of the sprocket 60 wheels,

Fig. 3 is a vertical sectional view of the mechanism shown in Fig. 1, 55

Fig. 4 is a bottom view of the handle showing the central disc,

Fig. 5 is face view of the locking mechanism, showing the equalizing spring,

Fig. 6 is a sectional view through the handle and the recess plate,

Fig. 7 is a similar view with the thumb piece lowered,

Figure 8 is a perspective view of the cam plate employed, 65

The entire mechanism shown in the drawings is mounted on a frame comprising a vertical plate, 1, having an off-set brace 1' and both provided with flanges 1'' to secure them to the frame 2 of the vehicle or its door. 70 Two sprocket wheels 3 and 4 are loosely carried by the studs 5 which are riveted to the plate 1.

Integral with the wheel 3 is a gear wheel 6 meshing with and driven by a pinion 7. 75

Adjacent to wheels 3 and 4 is a large sprocket wheel 8 carrying on its inner side a spiral spring 9, one end of which is secured to the wheel by a stud 10 and the other end of the spring is attached to a hub 80 11 pivoted on the rivet 12 and adjustable by means of the screw 13 passing through the arcuate slot 14 of which the rivet 12 is the centre and by loosening the screw 13 the wheel may be swung to the left and the 85 chain 15 removed or adjusted. This means may also be employed to loosen the chain 15 or tighten it and the spring is held against the wheel 8 by means of clips 8'.

One of the links of the chain 15 carries 90 a lateral stud 16 as shown in Fig. 3, having a head 17, said stud being adapted to enter the slot 18 of a hinged cam plate 19 which swings on a pintle 20 carried by eyes 21 on the lower edge of the window frame 22 carrying the pane 23. As shown in Figure 8, cam plate 19 has its slot 18 open at the right hand end, as at 50, so that the stud 16 may pass freely into and out of said slot. The lower portion of the wall of the slot is preferably cut away, as at 51, for facilitating the passage of the stud. Adjacent the opening 50 the upper portion of the wall of the slot is cut away to provide a surface portion 52 which is inset somewhat with respect to the 105 surface portion 53, and these two surface

portions are connected by a relatively inclined surface portion 26.

A spring 24 surrounds the pintle 20 and serves normally to press the lower portion 5 of the cam plate toward the chain 15. This spring serves also, therefore, to press the upper portion of the cam plate, and with it the lower portion of the window frame, outwardly in a direction away from the chain.

10 The window frame 22 is formed with an overhanging ledge portion 54 at its outer surface disposed for engaging over a stationary bar 25 which is carried by the outer wall portion 55 of the vehicle body.

15 When the window sash is at rest in its elevated position the portion 54 rests wholly upon the bar 25. At this time the stud 16 is substantially in the position shown by the dotted line representation thereof indicated 20 by 56 in Fig. 1.

In order to lower the sash the chain 15 is operated so that the stud moves from the position 56 through the open end 50 of the slot 18 and into engagement with the edge surface 57 of the slot 18. By reason of the relatively inclined disposition of the upper lead 58 of the chain this movement of the stud is such that the stud after engaging the surface 57 will lift said surface, and with it the 25 window sash and the part 54, a suitable distance to disengage the part 54 from the part 25. By the time the sash has been thus lifted the head 17 of the stud will move into engagement with the inclined surface 26 of the cam plate and in riding over said surface 26 will press back the upper portion of the cam plate, and with it the window sash. By 30 the time the head 17 begins to ride upon the surface 53 of the cam plate the part 54 will 35 stand entirely out of the path of the bar 25. The stud has by this time passed its highest point upon the sprocket 3 and begins to descend with the vertical leg 58 of the chain meanwhile riding to the extreme left hand 40 end of the slot and holding the cam plate pressed substantially flush with the chain. In its downward movement the portion 54 will 45 pass freely inside the bar 25 and the tension of the spring 24 will serve to hold 50 the cam plate and the parts related directly thereto under sufficient tension to prevent rattling at all times.

When it is desired to return the window to its upper position the chain is simply 55 moved to carry the stud upwardly. As the stud approaches its uppermost position and rounds the sprocket 3 the part 54 will have again assumed a position in a plane above the bar 25. Then as the stud is moved to the 60 right along the slot its head 17 travels down the incline 26 and allows the spring 24 to press the part 54 outwardly over the bar 25. Movement of the stud downwardly along the inclined leg 59 of the chain to the position 65 56 thereupon allows the window to move

downwardly so that the part 54 settles firmly over the bar 25 again, the spring 24 at all times continuing its function of preventing rattling of the window frame, even after the part 54 has settled in its final position upon 70 the bar.

The pinion 7 is operated by the handle 27 whose spindle 28 is secured by a screw to the disc 29 with two teeth 30 and adapted to rotate in the plate 31 secured in the frame 75 of the vehicle. On the inner side of the plate 31 is secured a ring 32 with inner serrations or teeth 33 while beyond the ring is a disc 34 attached by means of the spindle 35 with the pinion 7.

A face view of the disc 34 and ring 32 is shown in Fig. 5 and it will be seen that the disc carries pivoted pawls 36 which normally engage the teeth 33, being forced into engagement therewith by the spring 37 carried by a stud 38. The disc has in its upper end a perforation 39 and in its lower end the slot 40 in which is located a compensating spring 41 with a loop 42 for the reception of one of the teeth 30 while the other tooth 90 plays in the perforation 39.

While the handle 27 is in its normal position, tooth 30 in the perforation 39 is located between the upper ends of the pawls 36 and they engage the teeth 33, but when 95 the tooth is moved against one of the pawls said pawl is released from the teeth of the ring and the disc with the pinion 7 is allowed to rotate in the direction of that pawl and to rotate the sprocket wheel 3 and move the 100 chain so that the stud 16 moves the window sash up or down.

After pressure of the hand against the handle 27 is relieved, the spring 41 will cause the handle to again move to an intermediate 105 or neutral position with its teeth 30 out of engagement with the pawls. The spring 37 will then cause both pawls to again stand in engagement with the teeth 33 so that further rotation of the pinion 7 will be obstructed. In this way the window may be held positively supported in any intermediate position to which it may be purposely moved by the handle 27.

In case that the window is being moved 115 downward its weight is compensated for by the spring 9 and when the link carrying the stud reaches the bottom of its sprocket in the vehicle body a finger 43 carried by the chain comes in contact with a stop 44 and the only 120 movement then possible is the elevation of the sash.

At the outer end of the handle 27 is a thumb piece 45 to manipulate the same and which is held in its operative position by the 125 spring 46 having a perforation 47 near its outer end into which fits the pointed ball 48 of the thumb piece. When it is desired to move the thumb piece into such position as to prevent its catching and damaging cloth- 130

ing or other fabrics, the thumb piece may be turned down into the position shown in Fig. 7.

The operation of the device is as follows:

- 5 The drawings show the stud 16 in the slot and having passed the cam face 26 it has elevated and retracted the sash so that it is now in position to descend into the pocket. On further turning the handle 27 the stud 10 passes to the extreme left of the slot 18 and its link carries it down the side of sprocket 3 to the bottom of the pocket with the sash, and the weight of the latter is supported by the spring 9 because the chain turns the 15 wheel 8 and puts the spring under further tension until the chain is arrested by the stop 44.

When it is desired to return the sash to the window, the handle is turned, one of the 20 teeth 30 releases the proper pawl 36 and the pinion 7 rotates the gear wheel 6 and the sprocket 3 and the chain with the stud moves upward carrying the sash and the stud 16. When the proper position is reached by the 25 sash, it passes down the incline of the cam face of the slot 18 and the spring 24 throws the overturned edge 54 of the window frame outward into position to engage the bar 25. When the stud passes further out of the slot, 30 the sash is pulled onto the bar 25 and covers the window opening. There is no further need to turn the chain in that direction so the operator will cease turning the handle, but the stud or its link will eventually engage the stop 49 at the end of the cam plate and drop slightly so as to leave the sash resting on the bar 25.

To take out the glass channel 22, a further movement of the handle releases the 40 stud from the plate entirely.

As many changes could be made in this construction without departing from the scope of the following claims, it is intended that all matter contained in the above description, or shown in the accompanying drawings shall be interpreted as illustrative only and not in a limiting sense.

What I claim is:

1. In a closure operating mechanism, the 50 combination with a slidably mounted and laterally displaceable closure member, of operating means for said closure member, connections between the closure member and said operating means including a resiliently operated part constructed normally to urge the closure member toward its laterally displaced position, and the operating means comprising a part for controlling the effectiveness of said connections to laterally displace the closure member.

2. In a closure operating mechanism, the 55 combination with a slidably mounted and laterally displaceable closure member, of operating means for said closure member, connections between said closure member and

said operating means including a resiliently operated part arranged to exert a pressure against the operating means and a resultant pressure against the closure member thereby tending to displace the closure member laterally, the operating means comprising a part operable at one time to overcome said tendency and thereby to retain the closure member against lateral displacement, and operable at another time to permit said tendency to be exerted.

3. In a closure operating mechanism, the combination with a slidably mounted and laterally displaceable closure member, of operating means for the closure member, connections between the closure member and said operating means including a part pivotally connected with the closure member, means resiliently urging said pivotally connected part against the operating means for producing a resultant pressure tending to displace the closure member away from said operating means, said pivotally connected part having a cam face thereon, and said operating means comprising a part adapted to engage said cam face and to cooperate therewith for moving said pivotally connected part against said mentioned pressure.

4. In a closure operating mechanism, the combination with a slidably mounted and laterally displaceable closure member and a frame therefor having a part into overhanging relation with which the closure member moves upon lateral displacement of the closure member, of operating means for the closure member, connections between the closure member and said operating means including a part pivotally connected with the closure member, means resiliently urging said pivotally connected part against the operating means for producing a resultant pressure tending to displace the closure member laterally away from said operating means, said operating means comprising a chain, means by which to move the chain, a lug carried by and projecting from the chain into engagement with said pivotally connected part for sliding said closure member in response to certain movements of the chain, said lug having a portion disposed for engaging said pivotally connected part in a manner to cooperate therewith for permitting said pivotally connected part to displace the closure member laterally during a further movement of the chain.

5. In a closure operating mechanism, the combination with a slidably mounted and laterally displaceable closure member, of operating means for said closure member, connections between said closure member and said operating means including a resiliently operated part arranged to exert a pressure against the operating means and a resultant pressure against the closure member thereby

tending to displace the closure member laterally; and the operating means comprising a part for controlling the effectiveness of said resiliently operated part to laterally 5 displace the closure member.

6. In a closure operating mechanism, the combination with a slidably mounted and laterally displaceable closure member, of operating means for said closure member, connections between said closure member and said operating means including a resiliently operated part arranged to exert a pressure against the operating means and a resultant pressure against the closure member thereby 10 tending to displace the closure member laterally; and the operating means comprising a movable member, means to manually move said member, and a lug rigid with said member adapted to move therewith for controlling the effectiveness of the resiliently operated part to laterally displace the closure member. 15

7. In a closure operating mechanism, the combination with a slidably mounted and laterally displaceable closure member, of operating means for said closure member, connections between said closure member and said operating means including a part pivotally connected with the closure member, means resiliently urging said pivotally mounted part against the operating means for producing a resultant pressure tending to displace the closure member away from said operating means, and said operating means comprising a part for controlling the effectiveness of said pivotally mounted part to displace the closure member. 25

8. In a closure operating mechanism, the combination with a slidably mounted and laterally displaceable closure member and a frame therefor having a part into overhanging relation with which the closure member moves upon lateral displacement of the closure member, of operating means for the closure member, connections between the closure member and said operating means including a part pivotally connected with the closure member, means resiliently urging said pivotally connected part against the operating means for producing a resultant pressure tending to displace the closure member laterally away from said operating means, said operating means comprising a chain, means by which to move the chain, a lug carried by and projecting from the chain into engagement with said pivotally con- 30

nected part for sliding said closure member in response to certain movements of the chain, and said lug having a portion for engaging said pivotally connected part in a manner to hold said pivotally connected part tensioned to thereby avoid rattling of the parts. 60

9. In a closure operating mechanism, the combination with a slidably mounted closure member, of operating means for said closure member comprising an endless chain, a pair of sprockets spaced apart over which said chain passes, means for moving said chain about said sprockets, a part carried by the closure member having a slot therein, a connecting member carried by said chain engaging within said slot so as to slide the closure member as said chain is operated to move said connecting member along one lead of said chain, and a further sprocket over which the chain passes being arranged laterally from one of said other sprockets whereby to provide a lead of the chain disposed for moving said connecting member longitudinally along the slot, and the connecting member having a portion disposed for engaging one wall of the slot during movement of said connecting member along said last mentioned lead of the chain for producing a movement of the closure member, said slot being open at one end, and said connecting member being arranged to move outwardly through the open end of said slot by movement of the connecting member along said last mentioned lead of the chain to thereby disconnect the closure member from the chain. 70
